(57) **CLAIM**

The ornamental design for a basketball court pet bed, as shown and described.

DESCRIPTION

FIG. 1 is a perspective view of a basketball court pet bed showing my new design.

FIG. 2 is a top view of the basketball court pet bed.

FIG. 3 is a front elevation view of the basketball court pet bed.

FIG. 4 is a right side elevation view of the basketball court pet bed.

FIG. 5 is a left side elevation view of the basketball court pet bed.

FIG. 6 is a rear elevation view of the basketball court pet bed.

FIG. 7 is a bottom view of the basketball court pet bed; and, FIG. 8 is another perspective view of the basketball court pet bed.

The broken lines shown in FIG. 8 show a logo that is illustrative of environmental structure and form no part of the claimed design.
